UNITED STATES PATENT OFFICE.

BERNARD RINTEL SIMMONS, OF BIRMINGHAM, ENGLAND.

FASTENING DEVICE.

1,124,540.

Specification of Letters Patent.

Patented Jan. 12, 1915.

Application filed October 16, 1911. Serial No. 654,815.

To all whom it may concern:

Be it known that I, BERNARD RINTEL SIMMONS, a subject of the King of Great Britain, residing at 21 Vyse street, Birmingham, 5 in the county of Warwick, England, manufacturer, have invented certain new and useful Improvements in or Relating to Fastening Devices, of which the following is a specification.

10 This invention comprises improvements in or relating to hat pin heads, buttons, brooches, badges and like articles.

In order that this invention may be clearly understood and more easily carried into 15 practice, I have appended hereunto a sheet of drawings, upon which:—

Figure 1 is a side elevation of a hat pin constructed in accordance with the present invention. Fig. 2 illustrates in elevation the 20 three parts thereof disassembled, viz. the cup-shaped body, the dome-shaped part, and the locking ring. Fig. 3 is a vertical section through the hat pin illustrated in Fig. 1. Fig. 4 is a vertical section through the locking 25 ring. Fig. 5 is an inverted plan of the locking ring illustrated in Fig. 4, showing same partly formed. Fig. 6 is a vertical section through the cup shaped body. Fig. 7 is a plan of the cup shaped body shown in 30 Fig. 6.

In this invention which is shown only as a hat pin band a cup-shaped body A is pressed up from sheet metal, said cup-shaped body having three or other suitable number of 35 projections a^1 standing out from the periphery of the cup. Said cup or body is provided with a shank a^2 in the case of a hat pin or button, or other suitable means of attachment.

40 A dome-shaped part B is arranged to lie inside the cup or bottom A and is stamped up from sheet metal, the outer face being convex and the inner concave. Said dome is incorporated to accommodate a piece of 45 textile material C so that in the case of a hat, a piece of the material with which the hat is trimmed can be inserted in the hat pin so as to harmonize with the trimmings.

The textile material is placed over the 50 outer face of the dome B and the remainder of the material is twisted up so as to draw the material tight over the outer face, the material thus twisted lying in the chamber intermediate the concave face of the dome B

and the back of the cup A as illustrated in 55 Fig. 3.

The dome B is held in position by a locking ring D with a quick detachable fastening, said ring being pressed up from sheet metal. The periphery of the blank is 60 formed with two, three or more eccentric parts d^1 between each of which a recess d^2 is cut, said recesses corresponding to the projections a^1 formed in the back A aforesaid. The blank is cupped at d^3 and the eccentric 65 parts d^1 subsequently rolled or turned inward in such a manner as to form resilient inclined guides d^4 , while the recesses intermediate these guides form slots for the entrance of the projections a^1 . By these means 70 the locking ring D may be attached to the bottom A in a very rapid manner as it is only necessary to place the two parts together and partially rotate same relatively to one another when the projections a^1 engage the inner edge of the inclined guides 75 d^4 and lock in the manner of a bayonet joint. The outer face of the locking ring is provided with a hole d^5 through which the textile covering C on the dome is visible, 80 the diameter of the said hole d^5 being less than the diameter of the dome B so that the locking ring presses on the convex face of the latter and securely holds it in position.

It will be obvious that when it is desired 85 to change the material C it is merely necessary to rotate the locking cap D withdraw same, remove the dome B and replace the textile material thereon with another piece, replace the dome B and locking cap D when 90 the operation is complete.

It will be obvious that instead of using a dome covered by textile material, miniatures, etc., can be placed in the pin brooch or the like.

What I claim as my invention and desire to secure by Letters Patent is:—

In a fastening device for an article of the class described, the combination with a hollow front plate having a rearwardly rounded 100 peripheral portion and adapted to support an ornamental fabric covering having its free margins folded behind and into the hollow of said plate, a band having a gripping portion reduced in size with respect 105 to the rounded peripheral portion to frictionally grip and stretch the fabric tightly over the outer face of said plate as the band

is forced rearwardly thereabout, and a cup-shaped base closing the rear portion of said band and inclosing the inwardly folded marginal portions of said fabric, said band and cup having resilient cam coacting circular portions for maintaining the band in frictionally gripped relation with said fabric and locking the parts in assembled relation

upon relative rotative adjustment of said cup and band, substantially as described. 10

In witness whereof I have hereunto set my hand in the presence of two witnesses.

BERNARD RINTEL SIMMONS.
